COMBINED BLADE GUARD AND SUPPORT FOR A FAN OR THE LIKE

Louis J. De La Marter, Mansfield, Ohio, assignor to Westinghouse Electric Corporation, a corporation of Pennsylvania

Filed Jan. 14, 1966, Ser. No. 604

Term of patent 14 years

(Cl. D62—4)

FIGURE 1 is a perspective view of a combined blade guard and support for a fan representing my new design;

FIG. 2 is a front elevational view of the guard and support shown in FIG. 1;

FIG. 3 is a top plan view of the design shown in FIG. 2;

FIG. 4 is a side elevational view of the design shown in FIG. 2;

FIG. 5 is a rear elevational view of the design shown in FIG. 2; and

FIG. 6 is a bottom plan view of the design shown in FIG. 2.

The dominant features of my design reside in the portions shown in full lines.

I claim:

The ornamental design for a combined blade guard and support for a fan or the like, as shown and described.
